H. L. KEELER

BURGLAR ALARM

Filed June 11, 1923

Inventor.
Henry L. Keeler
By *AM Sturgeon*
atty

UNITED STATES PATENT OFFICE.

HENRY L. KEELER, OF LUNDYS LANE, PENNSYLVANIA.

BURGLAR ALARM.

Application filed June 11, 1923. Serial No. 644,695.

To all whom it may concern:

Be it known that I, HENRY L. KEELER, a citizen of the United States, residing at Lundys Lane, in the county of Erie and State of Pennsylvania, have invented certain new and useful Improvements in Burglar Alarms; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 This invention relates to alarms and has for its object the provision of mechanism adapted to sound an alarm when a guard wire is tampered with, either by a person colliding therewith or breaking it.

20 The object of this invention is to provide a picket alarm in which a picket wire circumscribes the area to be protected, which will cause the trigger mechanism to operate when a person collides with the wire, or

25 when the wire is cut or broken, the alarm being sounded in either case.

The features of my invention are herein-after fully explained and pointed out and are illustrated in the accompanying drawings in which:

Figure 1 is a vertical central section showing the mechanism set in position for tripping.

Figure 2 is a plan view of the same with a portion of the guard wire broken away.

Figure 3 is a longitudinal section of a cartridge holder removed from the device.

In these drawings A indicates a base plate upon which is secured a tube B by means of straps A', said tube having a longitudinal slot b cut therein from each end toward the intermediate portion thereof.

In the intermediate portion of the tube A is a transverse post C upon which is placed a lever D which is provided with arms d and d'. In the arm d is placed a stud post d² and on the under side of the arm d' is secured a transverse block d³ the inner edge of which is a segment of a circle having the 50 axis of the post C for its center.

Within the tube B are placed sliding bolts E and E' the bolt E being provided with a stud post e with which the stud post d² engages as shown in Fig. 1. The bolt E' is

also provided with a stud post e' upon which a roller e² is mounted and adapted to engage the curved edge of the block d³ on the lever D as shown in Fig. 1.

Upon the front ends of the bolts E and E' is provided heads e³ which are firmly secured thereon and having a sliding fit in the tube B. Upon the bolts E and E' are placed rings F through which the bolts E and E' will slide freely. The rings F fitting in the tube B snugly and are secured in their desired position therein by means of screws f.

Between the heads e³ on the bolts E and E' and the rings F are placed springs G which are compressed when the bolts are drawn inwardly and are held by the stud posts d² and block d³ on the lever D. It indicates stud posts secured in the heads e³ which project through the longitudinal slots b in the tube B and are for the purpose of forcing the bolts E and E' backward when setting the mechanism as hereinafter described.

In each end of the tube B I place a cartridge holder J which holders are interchangeable and are provided with stud posts J' which project through the longitudinal slot b and enter the transverse slots J² cut in the wall of the tube B. In the cartridge holder I place blank cartridges K see Fig. 3.

L indicates a spring attached to the lever D and to a post L' on the base plate A, and M indicates a tripping wire secured to the lever D and extending therefrom to an anchor M' secured at such distant point as may be desired. The spring L being arranged to maintain the wire M taut when the lever D is at right angles to the tube B as shown in Fig. 2.

In operation the cartridge holders J are removed from the tube B. The bolt E' is then pressed inward until the roller e² will pass behind the block d³ and the lever D is moved sufficiently to cause the block d³ to swing in front of said roller. The bolt E is then pressed inward and the lever D manipulated until the stud post d² swings in front of the post e on said bolt, thereby holding the bolt E in the position shown in Fig. 1, the block d³ permitting considerable movement of the lever D without releasing the bolt E'.

Previous to setting this device the wire M must be adjusted so that the lever D will

be maintained in the position thereof shown in Fig. 2. The resiliency of the spring L permitting the lever B to be swung toward the wire M during the setting of the bolts 5 hereinafter described.

Cartridges K are then placed in the cartridge holder J and the holders are then inserted in the ends of the tube B and the 10 posts J' swung over into the transverse slots J². Should the wire M be pressed against by some object colliding therewith, the lever D will be swung sufficiently to release the bolt E which will explode the cartridge K at that end of the tube B. Continued 15 pull on the wire M will cause the lever D to swing far enough to cause the block d³ to release the bolt E' which will explode the cartridge K in the opposite end of the tube B. Should the wire M be broken the spring 20 L will cause the lever D to swing in the opposite direction with a like result. In either case the cartridges K will be exploded in succession so that a positive alarm will be sounded.

25 Having thus fully described my invention so that others may utilize the same, what I

claim as new and desire to secure by Letters Patent is:

1. In a device of the class described, a tube, having a longitudinal slot in the wall thereof, a trigger lever mounted on said tube, a spring pressed bolt within said tube, a stud post on said bolt projecting outwardly through said slot, means on said trigger lever to engage said stud post, and means to operate said trigger lever to release said spring pressed bolt.

2. In a device of the class described, a tube, means to support a cartridge in each end of said tube, a pair of spring pressed bolts adapted to operate independently against each of said cartridges, a trigger lever, means thereon adapted to engage each of said bolts and retain them in set position, a spring adapted to operate said trigger lever in one direction, and a trip wire adapted to retain said lever in set position against said spring and to operate the same in the opposite direction.

In testimony whereof I affix my signature.

HENRY L. KEELER.
